E. ENDERES

SPLITTING SHEAR

Filed May 29, 1924

INVENTOR
ERNST ENDERES

BY *Carl M. Sinclair*

ATTORNEY

UNITED STATES PATENT OFFICE.

ERNST ENDERES, OF ALBERT LEA, MINNESOTA.

SPLITTING SHEAR.

Application filed May 29, 1924. Serial No. 716,647.

To all whom it may concern:

Be it known that I, ERNST ENDERES, a citizen of the United States of America, and resident of Albert Lea, Freeborn County, Minnesota, have invented a new and useful Splitting Shear, of which the following is a specification.

The object of this invention is to provide an improved construction for a traveling 10 shear adapted for cutting sheets of metal and the like.

A further object of this invention is to provide improved means for actuating the movable blade.

15 A further object of this invention is to provide an improved form of track on which the frame and blade may travel in the cutting operation.

A further object of this invention is to 20 provide improved means for forming a traveling connection between the shear frame and track.

A further object of this invention is to 25 provide improved means to cause the frame and members carried thereby to advance by step-by-step movement along the track as the blade is actuated.

30 My invention consists in the construction, arrangement and combination of elements hereinafter set forth, pointed out in the claims and illustrated by the accompanying drawing, in which—

Figure 1 is a plan view of the complete device. Figure 2 is a side elevation of the 35 same, portion of the actuating lever and track being broken away to economize space. Figure 3 is a longitudinal section, on an enlarged scale, on the line 3—3 of Figure 1. Figure 4 is a cross-section, on an enlarged 40 scale, on the line 4—4 of Figure 1. Figure 5 is a detail section on the line 5—5 of Figure 2, on an enlarged scale.

In the construction of the device as shown 45 the numeral 10 designates a channel beam of any desired length, which forms the principal part of the track and is arranged on edge, with its open face directed laterally. A frame 11, preferably a casting of irregular shape but rather flat, is arranged on 50 edge alongside the open face of the channel beam 10 and is adapted for travel lengthwise thereof. The frame 11 preferably is formed with an integral offset portion 11' projecting toward the channel 10 and of 55 substantially the same vertical dimension as said member, the main portion of the frame

thus being spaced somewhat from the plane of the channel. Journaled on the face of the offset portion 11' of the frame, as by means of shouldered bolts 12, are a pair of 60 upper rollers 13 and a pair of lower rollers 14, projecting within the channel 10 and adapted for traveling contact, respectively, with the upper and lower flanges of said channel. The rollers 13, 14 may be held 65 in the channel 10 by any suitable means, in this instance angle bars 15, 16 mounted on the margins of the upper and lower flanges respectively of said channel, extending longitudinally thereof and secured by rivets 70 17. One flange of each angle bar 15, 16 projects across the edge of the channel flange on which it is mounted and extends behind the rollers 13 or 14, as clearly shown in Figure 4, thus preventing displacement of 75 the rollers from the channel by lateral movement and serving to retain the frame and members carried thereby in position relative to the track. The inwardly projecting flanges of the angles 15, 16 are received in 80 rabbets 18, 19 in the adjacent face of the frame member 11' so that the frame may be mounted close to the channel.

Pivoted to the forward upper portion of the frame 11, by means of a bolt 20 ex- 85 tending through said frame and a bracket 21 mounted thereon, is a socket member 22 having an upwardly opening socket in which a lever or handle 23 is mounted. Below the socket member 22 the frame 11 is 90 formed with a forwardly opening recess 24, and a cutter arm 25 is mounted on that face of the frame adjacent the track, pivoted at one end on a bolt 26 in said frame, and its free end is adapted for oscillatory move- 95 ment across said recess in a plane parallel with the frame. A cutting blade 27 is attached to the free end of the cutter arm 25, on that face adjacent the track, and is adapted to cooperate with a stationary blade 100 28 carried by the adjacent portion of the frame at the lower side of the recess 24. Forwardly of the pivot 20, the lower face of the socket member 22 is formed with a curved cam margin 29 adapted for rolling contact with the upper face of the cutter arm 25 and serving to exert downward pressure on said arm when the socket member is oscillated in a forward direction by manipulation of the handle 23. The movable blade 27 is thus caused to pass across the plane of the stationary blade 28 and

effect a cutting operation on a substance which may be located between them. A link 30 is pivoted at 31 to the socket member 22 and at 32 to the free end portion of the cutter arm 25, and it is the function of said link to lift the said arm and blade 27 when the handle 23 and socket member are oscillated in a reverse direction.

A bar 33 is arranged parallel with the upper portion of the channel track beam 10, on that side opposite the frame 11, is slightly spaced therefrom and held in place by any suitable means such as bolts or screws 34. A pair of clamping devices are arranged 10 on the bar 33 and adjacent margin of the channel beam 10, each comprising a hook bolt 35 mounted between said members and having its hook engaging beneath the bar, said bolt being threaded at its upper end 15 and equipped with a wing nut 36, a washer 37 being mounted on the bolt beneath said nut and adapted to engage a marginal portion of a sheet to be cut or sheared. The clamping devices may be adjusted longitudinally of the track by loosening the nuts 36 and then caused to engage end margins of the sheet and hold it during the cutting operation by tightening the nuts.

A cable 38 is arranged in part within the channel track beam 10 and has one end secured to the forward end portion thereof at the point 39. The cable 38 passes rearwardly in the beam substantially on the median line thereof, passes between the upper rollers 13 and lower rollers 14 and out the rear end of the beam or through the open face thereof, depending upon the position of the frame. The cable 38 then extends around direction pulleys 40, 41 journaled 20 in a bracket 42 arranged transversely on the rear end of the frame 11 and extends forwardly alongside the outer face of the said frame, and is fastened to and adapted to be wound on a drum 43 journaled on said frame opposite the socket member 22 and on the pivot bolt 20 thereof. The drum 43 is provided with a peripheral ratchet 44 engaged and adapted to be turned by a dog 45 pivoted on the socket member 22, where- 25 by step-by-step rotary motion is communicated to the drum as the handle 23 is oscillated, in such manner as to cause the cable 38 to be wound on said drum, and the draft thus applied, the other end of the cable being fixed to the track beam, causes the frame and elements carried thereby to advance with step-by-step movement toward the forward end of the track, the rollers 13, 14 traveling 30 on the flanges of the track beam. It is apparent, therefore, that each forward movement of the handle 23 causes the cutter arm 25 to be depressed, by action of the cam surface 29 thereon, causing the blade 27 to pass across the blade 28 and cut a 35 section of a sheet which may be mounted

on the track and extend within the recess 24 of the frame; and that each rearward movement of said handle causes the cutter arm to be raised, through the link 30, and also causes the dog 45 to engage a tooth of the ratchet 44 and advance the frame and members carried thereby in readiness for another cut. A detent 46 preferably is pivoted on the frame 11, and is in engagement with the ratchet 44 to prevent undesirable reverse movement of the ratchet and drum.

When the frame and cutting elements have advanced to the forward end of the track, or to the extent desired, the detent 46 is 80 released and the frame moved manually rearwardly of the track, the cable unwinding from the drum during such movement. If for any reason it is desired to separate the frame and cutting elements from the track, 85 it may be accomplished by continuing the rearward movement until the rollers 13, 14 pass out of the rear end of the channel track beam and are no longer confined by the angle bars 15, 16.

I prefer to mount the cutting arm 25 in such manner that it may be accurately and positively adjusted laterally relative to the frame 11 and stationary blade 28. For this purpose a pair of adjusting blocks 47, 48 are provided, one near each end of the cutting arm, one of which is shown in Figure 5. The blocks 47, 48 are of rectangular form and are set in recesses in the face of the frame 11 and for each of said blocks 95 a pair of set or adjusting screws 49, 50 are employed, which screws are threaded into and through the frame from the opposite side and engage in holes bored in the inner faces of the blocks, by which means the blocks 100 may be adjusted and consequently move the cutting arm and space it relatively to the frame. Lock nuts 51 on the outer ends of the adjusting screws 49, 50 tend to preserve the adjustment when secured, by engagement 105 with the face of the frame member.

I claim as my invention—

1. A shear, comprising a track formed of a channel beam, a frame, rollers on said frame extended between and adapted for 115 travel on the flanges of said beam, said frame being formed with a recess, a stationary blade at one margin of said recess, an arm mounted for oscillation across said recess, a cutting blade carried by said arm and adapted to cooperate with the stationary blade, means for oscillating said arm, and means connected with the arm-oscillating 120 means for causing step-by-step travel of said frame.

2. A shear, comprising a track of channel form, a frame mounted alongside said track, rollers on said frame projecting within and adapted for travel on said track, angle-bars on said track overlapping said rollers, cut- 125 130

ting means carried by said frame, a lever pivoted on said frame and adapted to actuate said cutting means, a drum pivoted on said frame, a cable fixed at one end to said track, extending around said frame and adapted to be wound on said drum, and pawl and ratchet connections between said lever and drum for winding the cable on the latter as said lever is actuated.

10 3. A shear, comprising a track, a frame arranged for travel relative to said track, cutting means carried by said frame, a bolt transversely of said frame, a lever pivoted on said bolt and adapted to actuate said cutting means, a drum pivoted on said bolt independent of said lever, a cable fixed at one end to said track, extending around said frame and adapted to be wound on said drum, a ratchet carried by said drum, and a pawl on said lever adapted to rotate the drum when said lever is actuated, whereby the cable is wound on the drum and the frame and cutting devices are caused to advance as the cutting operation progresses.

15 4. A shear, comprising a track formed of a channel beam arranged on edge, a frame having a member extended toward and adapted for travel relative to said beam, rollers journaled on said frame member and extending within said channel track and adapted for rolling contact with the upper and lower flanges thereof, angle-bars on said channel track to prevent separation of the rollers therefrom by lateral movement, cutting means carried by said frame, and means to cause said frame to advance on the track as the cutting means is actuated.

20 5. A shear, comprising a track, a frame mounted alongside and adapted for travel longitudinally of said track, said frame be-

ing formed with a forwardly opening recess, a stationary blade carried by the frame at the lower margin of said recess, an arm pivoted on said frame and adapted for movement across said recess, means for adjusting said arm laterally of the frame, a cutting blade carried by said arm, a lever fulcrumed on said frame and formed with a cam face adapted to engage and depress said arm, and pivotal connections between said lever and arm for raising the latter.

25 6. A shear, comprising a track, a frame mounted alongside and adapted for travel longitudinally of said track, an arm pivoted on said frame, adjusting means carried wholly by the frame for adjusting said arm laterally, a cutting blade carried by said arm, a lever fulcrumed on said frame and formed with a cam face adapted to engage and depress said cutting arm when the lever is oscillated in one direction, a link pivotally connecting said lever and arm and adapted to raise the latter when the lever is oscillated in the opposite direction, and means connected with the lever for causing the frame to advance on the track a step at a time as the lever is oscillated in reverse direction.

30 7. In a shear having a frame member and a cutting arm parallel therewith, adjusting means comprising a block set in a recess in said frame member and engaging said arm, and an adjusting screw threaded through said frame member and in engagement with said block.

35 Signed at Albert Lea in the county of Freeborn and State of Minnesota, this 18th day of March, 1924.

40 ERNST ENDERES.
